UNITED STATES PATENT OFFICE

114,550

DESIGN FOR A COMBINED COFFEE MAKER AND TEAPOT OR SIMILAR ARTICLE

Walter B. Moore, West Lafayette, Ohio

Application January 19, 1939, Serial No. 82,448

Term of patent 7 years

To all whom it may concern:

Be it known that I, Walter B. Moore, a citizen of the United States of America, residing at West Lafayette, in the county of Coshocton and State of Ohio, have invented a new, original, and ornamental Design for a Combined Coffee Maker and Teapot or Similar Article, of which the following is the specification, reference being had to the accompanying drawing, forming a part thereof.

I claim:

The ornamental design for a combined coffee maker and teapot or similar article, substantially as shown.

WALTER B. MOORE.
